UNITED STATES PATENT OFFICE.

SAMUEL CHRISTOPHER McKEOWN, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY.

IGNITION-DYNAMO.

1,232,347.

Specification of Letters Patent.

Patented July 3, 1917.

Application filed July 12, 1913. Serial No. 778,727.

To all whom it may concern:

Be it known that I, SAMUEL CHRISTOPHER McKEOWN, a citizen of the United States, residing at Sumter, in the county of Sumter 5 and State of South Carolina, have invented certain new and useful Improvements in Ignition-Dynamos, of which the following is a specification, reference being had to the accompanying drawing.

10 My invention relates to ignition dynamos and particularly to those of the magneto type. Its objects are: to provide an efficient magneto of few parts and simple construction, easy to assemble. There are other advantages such as no moving wire or sliding contacts, the production of a magneto of the inductor type with only a single air gap, and improved means for advancing and retarding the spark.

15 Figure 1 shows a magneto in section, embodying my invention. Fig. 2, a section of same on the line A B, Fig. 1.

20 1 denotes a non-magnetic base, on which is secured in any suitable manner the permanent magnet 2, the poles of which are provided with the usual pole shoes 3 and 4. Attached to the base are the non-magnetic plates 5 and 6 which support a core structure 7 preferably of laminae. The inner 25 cheeks of the extremities 8 and 9 of the core are parallel, and in contact therewith are the rotor elements 10 and 11 of magnetizable material, axially separated by the non-magnetic block 12. Any suitable shaft arrangement may be employed for the rotor, such as the shafts 13 and 14 journaled either in the core 7 or the plates 5 and 6.

25 Any suitable winding 15 is placed about the core 7. A suitable location is as shown 40 in Fig. 2 although any other arrangement may be employed.

To enable the spark to be advanced and retarded, I provide a cylinder between the rotor and the pole shoes of the magnet, 45 composed of the magnetic sections 16 and 17, and non-magnetic sections 18 and 19. A projecting handle 20 enables the cylinder to be rotated, and it is obvious how, by varying the position of this cylinder, the relative 50 position of the pole shoes 3 and 4 (to which the sections 16 and 17 simply form extensions) to the rotor are varied, thereby advancing or retarding the spark in the usual manner. In machines where it is not

desired to advance and retard the spark, the cylinder member may be omitted.

The operation of this magneto will be apparent from a study of the drawings. Supposing 3 to be of N polarity, and the rotor is moving to the left, Fig. 1, when 10 is 60 opposite 3, lines of force will flow from 3 into 10 to 9 through 7 to 8, into 11 and to 4, (disregarding the cylinder 16, 17). When the rotor is in the opposite position then the lines will flow from 3 to 11 to 8, through 7 to 9 to 10 and to 4. This causes alternate 65 reversals of flux through the core 7 which influence winding 15 in the usual manner.

I claim—

1. In an ignition dynamo, a U shaped 70 field magnet, a generating coil and a core therefor, and a rotor having a path of travel between the extremities of said core and comprising inductor elements axially magnetically separated from each other, said elements magnetized by the field magnet and 75 having their polarity reversed at each rotation.

2. In an ignition dynamo, a U shaped 80 core having extremities spaced apart, a rotor journaled to turn between said extremities, said rotor comprising magnetic elements, magnetically separated from each other and having continuous rotary magnetic relation with the side faces of said core 85 extremities, winding on said core, and a field magnet in inductive relation to said rotor, the arrangement being such that the polarity of each rotor element is reversed 90 at each rotation.

3. In an ignition dynamo, a U shaped 95 core structure having extremities spaced apart, a rotor journaled to turn between said extremities, extending longitudinally between the extremities of the core, and having suitable bearing supports, said rotor comprising a pair of axially separated magnetizable members having end surfaces in sliding contact with the inner faces of said core extremities independently of said bearing supports, together with a magnet in inductive relation to said rotor.

4. In an ignition dynamo, a core structure 100 having axially aligned apertures in opposite polar extremities, a rotor having shaft extensions journaled in said apertures, and having a main body adapted to be magnetized, a coil on said core structure and a

field magnet in inductive relation to said rotor, adapted to reverse the magnetization of the rotor body at each rotation.

5. In an ignition dynamo a substantially **U** shaped core structure carrying a winding and having axially alined bearing apertures in its extremities, a rotor journaled in said apertures and having end portions of magnetic material in magnetic and conductive relation respectively to the inner faces of said extremities but magnetically insulated from each other, together with a magnet in inductive relation to said rotor.

6. In an ignition dynamo, a **U** shaped core carrying a generator winding and having extremities spaced apart with the inner cheeks opposite and parallel to each other, and a rotor between said extremities having a right cylindrical path of rotation and end surfaces of magnetic material rotating in continuous magnetic relation with the inner parallel cheeks of said core extremities, but magnetically insulated from each other, together with a magnet in inductive relation 25 to said rotor.

7. In an ignition dynamo, a **U**-shaped core carrying a winding, a rotor having its axis of rotation in a plane with the extremities of said core and its path of travel entirely 30 within the space between said extremities, and a **U**-shaped magnet having its poles at right angles to the axis of rotation of said rotor and in inductive relation thereto.

8. In an ignition dynamo, a core member 35 having extremities spaced apart, journal bearings associated therewith, a rotor journaled in said bearings to turn between said extremities and extending from one to the other, said rotor comprising magnetizable 40 elements having rotary contact with the side faces of said extremities independently of the journal bearings, and a magnet in fixed inductive relation to said rotor.

9. In an ignition dynamo, a core member 45 having extremities spaced apart and forming bearing supports, a rotor journaled to turn between said supports and extending longitudinally between them said rotor comprising a pair of axially separated magnetizable members having end surfaces in sliding contact with the inner faces of said extremities independent of said bearing supports, together with a stationary magnet in normally fixed inductive relation to said 55 rotor.

10. In an ignition dynamo, a base, extensions on said base forming bearings, a fixed substantially **U**-shaped core member having

polar extremities and fixedly secured to said base, a generator winding on said member, 60 a magnet having its poles positioned at right angles to an axial line through said bearings, revoluble means comprising members in permanent magnetic relation to said polar extremities of said core member journaled in 65 said bearings for conducting the flux from said magnet poles to said core member, and means interposed between said flux-conducting means and said core member whereby the relative degree of angularity between 70 said polar extremities of the core member and the poles of said magnet may be varied for timing purposes, substantially as described.

11. In an ignition dynamo, a core member 75 having transversely alined apertures in its extremities, a rotary inductor embraced in an endwise position by said extremities, bearings for said inductor, and means supporting said bearings and core member, substantially as described.

12. An ignition dynamo comprising a **U**-shaped core member carrying a winding, a base of non-magnetic material, a magnet mounted upon said base, a rotary inductor 85 embraced by the extremities of said core member in an endwise position and having stub shafts which project through apertures in said member, and lateral bearing members supported by said base for supporting 90 said inductor and core members.

13. A magneto electric machine comprising a **U**-shaped permanent magnet, a **U**-shaped core member having apertures in its extremities on a line extending transversely 95 thereof, a rotor structure embraced by said extremities and comprising inductor elements, each of which in all angular positions is directly magnetically associated with one of said extremities, a non-magnetic base 100 supporting said magnet, rotor and core member, and means comprising a cylinder having alternately magnetic and non-magnetic sections interposed between said magnet and rotor structure whereby the magnetic 105 relation of the poles of said magnet to the extremities of said core member may be varied for timing purposes, substantially as described.

In testimony whereof I hereunto affix my 110 signature in the presence of two witnesses.

SAMUEL CHRISTOPHER McKEOWN.
